UNITED STATES PATENT OFFICE.

WILLIAM G. ESTEP, OF DUQUESNE, PENNSYLVANIA.

VALVE.

1,090,521.

Specification of Letters Patent. Patented Mar. 17, 1914.

Application filed November 27, 1912. Serial No. 733,907.

To all whom it may concern:

Be it known that I, WILLIAM G. ESTEP, a citizen of the United States, residing at Duquesne, in the county of Allegheny and 5 State of Pennsylvania, have invented a new and useful Valve, of which the following is a specification.

The present invention relates to improvements in valves, the primary object of this 10 invention being the provision of a novel form of spring closed valve, which is especially adapted to be used in connection with flush tanks.

A further object of the present invention 15 is the provision of a novel form of valve adapted to be connected to the outflow of a pipe, the same being normally held closed to be operated to permit the proper flow of water through the valve, such flow being 20 regulated so as to be steady and not intermittent, the same forming in reality a pressure reducing medium so that the flow of water under high pressure will be reduced to a gradual flow.

25 With the foregoing and other objects in view which will appear as the description proceeds, the invention resides in the combination and arrangement of parts and in the details of construction hereinafter described and claimed, it being understood that changes in the precise embodiment of the invention herein disclosed can be made 30 within the scope of what is claimed without departing from the spirit of the invention.

35 In the drawings Figure 1 is a sectional view through a low hopper flush tank with the present invention in operable relation thereto. Fig. 2 is a section taken on line 2-2 of Fig. 1. Fig. 3 is a vertical central 40 sectional view through the complete valve casing and valve with the parts in normally closed position. Fig. 4 is a sectional view illustrating a means whereby the valve may be seated by water pressure and the spring 45 may be dispensed with.

Referring to the drawings, the numeral 1 designates the outer casing of a flush tank hopper, while 2 designates the inner metal and water containing tank, both of which 50 are of usual construction. Led into the tank 2 is the supply pipe 3, while led thereaway from is the flushing conduit 4, the same being controlled by a buoyant ball valve 5

which is elevated through the medium of the operating lever 6, mounted in the upper end 55 of the journaling post 7. A rod 8 is connected to the opposite free end of the lever 6 and is operable exteriorly of the casing 1 through the means of the push button 9. Pivoted to the end of the lever adjacent the 60 rod 8 is a depending rod 10 whose button 11 limits the upward movement of the free end of the valve actuating lever 12, the detailed structure of which will presently appear.

65 The coupling member 13' of the valve structure is provided and is connected by any well known means to the outlet end of the water supply conduit 3, the lower end 13 being provided with the chamber 14 which 70 is sealed by the removable valve seat 15, which has seated thereupon the valve 16, whose spring 17 is of such a tension as to offer sufficient resistance to the inflow of water to reduce the pressure so that the objectionable outflow of water into the tank 2 will be removed and a steady constant flow 75 permitted thereinto. The spring 17 will be made of varying strength in order to operate the valve 16 according to the pressure 80 supplied through the conduit or pipe 3.

A channel 18 is formed through the base member 13' and enters the chamber 19 of the removable casing 20 which has its lower end detachably connected to the threaded 85 boss 21 of the member 13'. An outlet port 22 is formed concentrically in the upper end of the chamber 19 and leads through the duct 23 into the downwardly projecting outlet 24, said outlet 24 being so positioned as 90 to normally project the water below the level of the water within the tank 2, thus decreasing the noise, due to the inrush of water within the tank 2, to a minimum.

95 Formed integral with the threaded boss 21 and projecting upwardly and within the casing 20 is a stem 25 provided with the cupped member 26, and also the socket 27, said socket 27 being in axial alinement with the bore 28 formed in the upper end of the 100 casing 20 and constituting therewith a guide for the valve stem 29 which is permitted a vertical sliding movement. On this valve stem 29, as clearly shown, is carried the metal guiding disk 30 and the valve gasket 105 31 which is normally held by the spring 32

upwardly to close the port 22 and thus prevent the inrush of water from the casing or chamber 19 through the outlet port 24.

The operating lever 12 is journaled between the apertured lugs 33 formed integral with the casing 20 and has its integral plunger depressing lug 34 disposed to abut the upper end of the valve stem 29, so that when the push button 9 is depressed, the rod 10 will also be depressed and consequently depress the lever 12 to move the valve 31 from the valve seat 22 and thus permit the inrush of water through the port 23 into the outlet spout 24 of the casing 20.

15 In order to provide a means for permitting the automatic elevation of the operating lever 12 to release the stem 29 to the action of the spring 32 after a predetermined amount of water has entered the tank 2, a 20 lug 35 is formed integral with the lever 12 and has journaled between it and the projecting portion of the lug 34, a pin 36. Journaled within the apertured lugs 37 formed integral with the casing 20 is the float actuated lever 38 whose enlarged lower end is provided with a slot having the reduced end 40 and the enlarged end 41, this peculiar shaped slot embracing the pin 36 of the lever 12 so that when the float 43 connected 30 to the lever 38 by means of the rod 42, is in lowermost position, the pin 36 will be seated within the portion 40 of the slot and the lever 12 will be locked in its lowermost position to retain the valve 30 depressed 35 against the spring 32 and permitting the inrush of water into the tank 2. As soon as the water has reached a sufficient level to elevate the float 43, it is evident that the lever 38 will also be elevated so that the portion 41 above the portion 40 of the slot at the lower end of the lever 38, will permit the spring 32 to elevate the stem 29 and cause the pin 36 to seat within the enlarged portion 41 of the slot, thus automatically closing 45 the valve, and only after the necessary amount of water has been permitted to enter the tank 2.

The spring 32 is used primarily to assist in moving the valve 31 toward the seat 22, 50 the pressure fully seating the valve, and should it be desired the cup 26' may be perforated near its lower end as at 50 and the spring 32 dispensed with. By this means the pressure will enter the cup below the 55 plunger 30' to seat the valve 31'. This structure is illustrated in Fig. 4. In this form of valve, the pressure of the water at the outlet is reduced to relieve the same of the undesirable action where high pressure is used.

What is claimed is:

1. A valve, including an attaching member provided with an inlet channel there-through, a casing removably attached to the

member and into which the inlet channel 65 empties, said casing having a valve seated outlet port, a valve guiding and containing cup carried by the attaching member concentrically of and within the casing, a disk valve mounted in the cup in the nature of 70 a plunger, a stem carrying the disk valve, said stem extending in opposite directions upon each side of the valve and guided by the casing and the attaching member, said valve being disposed for movement into and 75 out of engagement with the valve seated port, a lever pivoted to the casing and disposed to engage the valve stem to move the valve from the valve seated port, a float actuated lever pivoted to the casing and at 80 right angles to the valve stem actuating lever, and coöperable means carried by both of said levers, whereby the float by its descending will lock the valve stem actuating lever in its lowermost position and will release the same when elevated by the rise of 85 the water.

2. A valve, including an attaching member provided with an inlet channel there-through, a casing removably attached to 90 the member and into which the inlet channel empties, said casing having a valve seated outlet port, a valve guiding and spring containing cup carried by the attaching member concentrically of and within the 95 casing, a spring in said cup, a valve stem slidably mounted in the casing and attaching member and concentrically of the cup, a valve carried by the stem within the cup and casing, said valve being normally held 100 by the spring upon the valve seated port, a lever pivoted to the casing and disposed to engage with the valve stem to depress the valve, a float actuated lever pivoted to the casing and at right angles to the valve 105 stem actuating lever, and coöperable means carried by both of said levers, whereby the float, by its descending will lock the valve stem actuating lever in its lowermost position and will release the same when elevated 110 by the rise of water.

3. A valve, including an attaching member provided with an inlet channel there-through, a casing removably attached to the member and into which the inlet channel 115 empties, said casing having a valve seated outlet port, a valve guiding and spring containing cup carried by the attaching member concentrically of and within the casing, a spring in said cup, a valve stem slidably mounted in the casing and attaching member and concentrically of the cup, a valve carried by the stem within the cup and casing, said valve being normally held by the 120 spring upon the valve seated port, a lever pivoted to the casing and disposed to engage with the valve stem to depress the valve, a float actuated lever pivoted to the casing and 125

at right angles to the valve stem actuating lever, said float actuated lever being provided with a cam slot in the end thereof, and a pin carried by the valve stem actuating lever and disposed within said slot to contact therewith to form a lock to hold the stem actuated lever depressed and the valve open when the float is in its lowermost position and so as to permit of the release of the

stem actuated lever upon the elevation of 10 the float.

In testimony that I claim the foregoing as my own, I have hereto affixed my signature in the presence of two witnesses.

WILLIAM G. ESTEP.
